J. M. MOTHERSALL,
LUNCH BOX.
APPLICATION FILED JAN. 2, 1918.

1,316,240.

Patented Sept. 16, 1919.

UNITED STATES PATENT OFFICE.

JOHN M. HOTHERSALL, OF BROOKLYN, NEW YORK, ASSIGNOR TO AMERICAN CAN COMPANY, OF NEW YORK, N. Y., A CORPORATION OF NEW YORK.

LUNCH-BOX.

1,316,240.

Specification of Letters Patent. Patented Sept. 16, 1919.

Application filed January 2, 1918. Serial No. 208,879.

To all whom it may concern:

Be it known that I, JOHN M. HOTHERSALL, a citizen of the United States, residing in Brooklyn, in the county of Kings and State 5 of New York, have invented a new and useful Improvement in Lunch-Boxes, of which the following is a specification.

This invention relates in general to lunch boxes and has more particular reference to 10 lunch boxes adapted to carry a thermos bottle as well as the usual sandwiches and other food.

The principal object of the invention is 15 the provision of a lunch box in which a thermos bottle may be readily and quickly positioned in the cover and removed for use and which when so positioned will not interfere with the packing of the usual contents in the body of the box.

20 Another object of the invention is the provision of such a box at low cost and having the general effect of a valise or traveling bag.

25 Other objects and advantages of the invention will be apparent as it is better understood from the following description when considered in connection with the accompanying drawing illustrating a preferred embodiment thereof.

30 On the drawings,

Figure 1 is a section through a lunch box embodying my present invention; and

Fig. 2 is a top plan view of the same with the cover in fully open position.

35 The lunch box shown on the drawing consists primarily of a body 4 of rectangular section form and a cover 5 hinged at one side at 6 along a side of the body and having a flange 7 adapted to close down over 40 the body, locking catches 8 being provided. The cover is campanulate in transverse section so that when it is closed the entire box resembles closely a valise or bag, a suitable 45 handle or hand grip 9 being provided on the top as is usual with hand bags. It is intended that a thermos bottle 10 be arranged in the cover with its outer round surface engaging in the concave portion of the inner face of the cover. An arm 11 50 preferably of spring metal is pivoted on an outwardly extending lug or ear 12 provided at the center of one side of the cover and near the box body. A pivotal connection of this arm with the ear is provided by a

55 rivet 13 of suitable character, the end of the arm lying above the ear so that the arm swings in a plane parallel to the axis of the box, although manifestly it might be otherwise arranged. At the other side *i. e.*, the front in the present instance, an ear 14 extends in toward the ear 12. The ear 14 is cut away as indicated at 15 to receive the end of the arm 11, lips 16 being thus provided to act as stops and prevent the arm from inadvertently becoming disconnected. 60 The yielding nature of the arm permits it to push the thermos bottle tightly against the cover so that the bottle has little tendency to become loose and the arm therefore cushions the bottle, thereby minimizing 65 danger of breakage. When it is desired to remove the bottle the end of the arm 17 which is engaged in the ear 14 is pressed up until free of the stop 16 and the arm is then swung around against the rear side of 70 the cover to permit the thermos bottle to be 75 lifted out.

75 It is thought that the invention and many of its attendant advantages will be understood from the foregoing description, and 80 it will be apparent that various changes may be made in the form, construction and arrangement of the parts without departing from the spirit and scope of the invention or sacrificing any of its material advantages, the form hereinbefore described 85 being merely a preferred embodiment thereof.

I claim:

1. A lunch box comprising a body, and a 90 cover hinged to the same, said cover being of campanulate form in cross section, a thermos bottle arranged parallel with the hinge of the cover and seated within the upper part of the same and held from side- 95 wise movement by the curved side walls of the cover, and a spring arranged across the lower part of the cover and movably connected with the sides thereof and bearing on the under side of the bottle to press the 100 latter into its said seat.

2. A lunch box comprising a body, and a cover hinged to the same, said cover being of campanulate form in cross section, a thermos bottle seated within said cover and held from sidewise movement by the curved side walls of the cover, and a spring arranged across said bottle at the inner side 105

thereof and acting to press the bottle toward the top of the cover and into its seat therein, said spring having at one end a pivotal connection with the cover so as to swing on a vertical axis and having at the other end a detachable connection with the cover which connection holds the spring against turning on its pivot, said connec-

tion being releasable by pressing the end of the spring upward. 10

In testimony whereof I affix my signature.

JOHN M. HOTHERSALL.
